[57] CLAIM

The ornamental design for an electronic whiteboard and photocopier, as shown and described.

DESCRIPTION

FIG. 1 is a front and right side perspective view of the electronic whiteboard and photocopier showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof, the left side elevational view being a mirror image thereof; and FIG. 7 is a sectional view thereof taken along the line 7—7 of FIG. 1.
